UNITED STATES PATENT OFFICE.

LUIGI CASALE, OF ROME, ITALY, ASSIGNOR TO CASALE AMMONIA COMPANY, OF LUGANO, SWITZERLAND.

APPARATUS FOR THE ELECTROLYSIS OF WATER.

Application filed July 19, 1922. Serial No. 576,104.

To all whom it may concern:

Be it known that I, LUIGI CASALE, a subject of the King of Italy, and residing at Rome, Italy, whose post-office address is via 5 del Parlamento No. 9, Rome, Italy, have invented certain new and useful Improvements in or Relating to Apparatus for the Electrolysis of Water, of which the following is a specification.

10 The electrolysis of water for the production of hydrogen and oxygen is continually increasing in industrial importance. The decomposition is usually effected by passing the current between metallic electrodes immersed in an alkaline electrolyte and separated by a diaphragm of asbestos cloth. The employment of this diaphragm, the object of which is to separate the two gases, reduces the output by increasing the resistance of the electrolyte, and represents a considerable loss, being very costly and requiring frequent renewal owing to the rapid wear. Various means for separating the two gases have already been investigated, 25 and V-shaped diaphragms on insulating material have been interposed between the electrodes; but the apparatus is thereby rendered more expensive and complicated, an inconvenience which has also been found attendant on other expedients, without however, giving a better yield in any instance.

The object of the present invention is to provide an apparatus for the electrolysis of water, in which no diaphragm is interposed between the electrodes, the two gases being separately guided by the currents set up in the electrolyte by the ascensional force exerted by the gases liberated, at the electrodes, in the interior of the liquid.

40 In this apparatus the current efficiency is therefore greater, not only because there is no diaphragm, but also because the electrolyte is not diluted, between the electrodes, by the tiny bubbles of escaping gas, and consequently, the conductivity of the liquid is uniform throughout its entire mass.

A typical electrolyzer according to the present invention is illustrated diagrammatically in the accompanying drawing, in 50 which Fig. 1 is a vertical longitudinal section through the electrolyzer, that is to say parallel with the electrodes, and Fig. 2 is also a section of the apparatus, but in the transverse direction. Fig. 3 is a vertical 55 section of a modified form of the device and

Fig. 4 is a horizontal section of the structure shown in Fig. 3.

The electrolyte is contained in a parallel-sided vessel 1, resting on insulating feet 2 and closed by a tight cover 3 having a gas tight connection 4 with the vessel 1. Below the joint the cover telescopes into the interior of the vessel for such a distance that it dips slightly below the level of the liquid.

60 Each electrode consists of a pile of a certain number of elements 5, each of which is composed of a strip of sheet iron slanting as shown in the drawing and bent in the horizontal plane so as to form a rectangular frame, the section of which, in the direction 65 of the longest side, is shown in Fig. 1, and extending substantially the full length of the containing vessel 1. The section along the shorter side is represented in Fig. 2 and shows each frame extending but a small 70 fraction of the total width of the containing vessel 1. Above the pile of elements 5 is a terminal element 6, exactly the same as the others except that it is of much greater height. Its upper surface projects above 75 the level of the liquid. All the elements 5 and the corresponding element 6 of the same electrode are connected together by small plates, as indicated by 7 and 8, terminating in two rods 9 and 10, which pass through 80 the stuffing glands 11 in the cover of the vessel, said rods being insulated and serving at the same time, as current leads and as supports for the electrodes. Each electrode thus resembles a parallelopiped bell, with 85 walls formed with gaps like jalousie and directed upwardly from the outside of the bell towards the interior. The electrodes are identical except for the two end electrodes, which may be regarded as formed 90 by dividing on a central longitudinal plane, an electrode built up in the manner described, and by facing the sectional plane in each of the two halves thus obtained with a sheet of metal as shown.

95 The cover of the vessel is provided with partitions 12 extending as far as the level of the liquid between the electrodes, so as to form in relation to each electrode a closed cell 13 over the liquid. Each cell is provided, in its upper part with a delivery tube 14. Of these tubes 14, assuming them to be numbered progressively, the even numbers terminate in a collector 15, and the odd numbers in another collector 16. The cur- 100 105 110

rent leads are arranged in such a manner that the electrodes are alternately anodes and cathodes.

The apparatus operates in the following 5 manner:

During the passage of the current, the tiny bubbles of gas liberated at the facing outer surfaces of two contiguous electrodes are collected in the interior of the respective 10 electrodes, in consequence of the specified special arrangement of said surfaces themselves. Hence, whilst the space between one electrode and the other is occupied solely by the electrolyte, the interior of each electrode 15 is occupied solely by the electrolyte, emulsified by the tiny bubbles of gas. In this way, two communicating columns of liquid are formed, of equal height but of different specific gravity, consequently the 20 system cannot be in equilibrium, and there is an ascending movement set up inside the electrodes and a descending movement between one electrode and the other.

The level of the liquid is regulated in 25 such a way that the ascending interior column passes beyond the element 6 and discharges outside said element thus separating the gas from the liquid which sinks to the lower level and serves to feed the descending 30 column. On the other hand, the descending column serves to feed the ascending column through the whole gapped surface of the electrodes and through the gaps 35 provided in the bottom of the electrodes 17 themselves.

In the modified construction shown in the Figs. 3 and 4 the electrolyzer comprises: A cylindrical vessel 18 supported on insulating feet 19 and containing the electrolyte; a 40 close fitting cover 20; a cathode formed by a cylindrical surface of sheet metal 21 and by another surface 22, also cylindrical, placed inside the former and provided with horizontal or sloping gaps, these two surfaces 45 being connected at the bottom by an annular base 23. The gapped portion does not extend as far as the surface of the liquid the upper part being solid. The gapped portion 50 may be replaced by a simple metal gauze.

The anode, which is arranged inside the cathode, is formed in exactly the same way, except that in this case the exterior surface is pierced whilst the interior surface is solid. In the upper part of the apparatus a median 55 cylindrical partition 24, secured to the inside of the cover, projects between the electrodes and divides the bell formed by the cover into two chambers, to each of which corresponds the upper extremity of an electrode 60 and each is provided with a tube 25, 26 for collecting the gases.

Each electrode is provided with a support and current lead as in the previous case.

The apparatus works in the same manner 65 as that already described, except that the

ascending currents pass into the interior of the electrodes and into the space situated between the confronting surfaces, whilst the descending currents pass on the outer side of the cathode and the inner side of the 70 anode.

Having now particularly described and ascertained the nature of my said invention and in what manner the same is to be performed I declare that what I claim is:— 75

1. In an apparatus for the electrolysis of water, electrodes having passages therein for the gases liberated at said electrodes adapted to separate said gases and to provide a path of uniform conductivity between 80 said electrodes.

2. In an apparatus for the electrolysis of water, an electrode comprising a column of spaced outwardly flared members.

3. In an apparatus for the electrolysis 85 of water, electrodes comprising the columns of spaced members adapted to direct the liberated gases into the interior of the columns and provide a circulation of the electrolyte between opposing electrodes.

4. In an apparatus for the electrolysis of water, electrodes comprising columns of spaced outwardly flared members adapted to direct the liberated gases away from the spaces between opposing electrodes. 90

5. In an apparatus for the electrolysis of water, cooperating electrodes adapted to direct the liberated gases away from the current path between said electrodes.

6. In an apparatus for the electrolysis of water, a container, a cover for said container having partitions dividing the space above the electrolyte into chambers, electrodes adapted to direct the liberated gases away from the space between opposing electrodes 100 to said chambers and conduits connected to said chambers. 105

7. In an apparatus for the electrolysis of water, a container, a cover for said container, conducting supports carried by said cover and electrodes comprising a plurality of spaced outwardly flared rectangular members carried by said supports. 110

8. In an apparatus for the electrolysis of water, a container, a cover for said container, conducting supports carried by said cover, means carried by said cover dividing the space above the electrolyte into chambers and electrodes carried by said supports having passages therein for directing liberated gases away from each other and to said chambers. 115

9. In an apparatus for the electrolysis of water, a container, a cover for said container, conducting supports carried by said cover and electrodes carried by said supports having passages adapted to direct the liberated gases from the current path between the electrodes. 125

10. In an apparatus for the electrolysis 130

of water, cooperating electrodes providing paths within the electrodes for the liberated gases such that a flow of electrolyte of uniform density is set up across the paths between the opposing electrodes.

11. In an apparatus for the electrolysis of water, cooperating electrodes having passages for the discharge of the liberated gases and electrolyte, said gases being separated from said electrolyte upon the discharge of said electrolyte over said electrodes.

12. In an apparatus for the electrolysis of water, cooperating electrodes adapted to cause a flow of the electrolyte over said electrodes to separate the liberated gases from the electrolyte.

13. In an apparatus for the electrolysis of water, a container, a cover for said container, conducting supports carried by said cover and electrodes carried by said support adapted to cause a flow of the electrolyte to separate the gases liberated at the electrodes.

14. In an apparatus for the electrolysis of water, a container, a cover for said container, conducting supports carried by said cover and an electrode carried by said sup-

ports comprising a column of spaced strips inclined upwardly and inwardly.

15. In an apparatus for the electrolysis of water, a container, a cover for said container, conducting supports carried by said cover and electrodes comprising a plurality of spaced hollow rectangular members having outwardly flared lower edges carried by said support.

16. In an apparatus for the electrolysis of water, cooperating electrodes having passages which direct the liberated gases away from each other to separate the gases and set up a flow of the electrolyte which aids in the separation of the gases.

17. In an apparatus for the electrolysis of water, cooperating electrodes having passages which direct the liberated gases away from each other.

In testimony whereof I have hereunto signed my name in the presence of two witnesses.

LUIGI CASALE.
